Inventor:

David N. B. Coffin Jr.

UNITED STATES PATENT OFFICE.

D. N. B. COFFIN, JR., OF NEWTON CENTER, MASSACHUSETTS, ASSIGNOR TO BOSTON FAUCET COMPANY.

FAUCET.

Specification of Letters Patent No. 17,604, dated June 16, 1857.

To all whom it may concern:

Be it known that I, DAVID N. B. COFFIN, Jr., of Newton Center, in the county of Middlesex and State of Massachusetts, have 5 invented certain new and useful Improvements in Faucets; and I do hereby declare that the following is a full, clear, and exact description of the same, reference being had to the accompanying drawings, which form 10 a part of this specification, and to the letters of reference marked thereon.

These improvements relate to the means for operating the valve, and mainly consist of an annular series of lifters or an inclined 15 surface or surfaces arranged upon a ring acting by and with the aid of a guide upon a removable pin in the valve-stem. The lifters being hung upon a pivot or resting flatly on the cap of the faucet, with or without 20 out an inclined surface above the pin by which to close the valve and hold it to its seat.

Index to the drawings.—Figure 1 is a vertical section of a faucet with my improvements applied, a part of the valve-stem and the pin being shown in full. Fig. 2 is an elevation of the guide broken from the cap, the view being taken at right angles with that of Fig. 1. Fig. 3 shows a section of the 25 series of inclines or lifters with a sectional elevation of the knob for operating the same. Fig. 4 is a plan of the lifters. Fig. 5 is a plan of the guide and the cap of the faucet, to which it is attached. Fig. 6 is a side elevation of the faucet complete. Fig. 7 is a 30 sectional elevation, and Fig. 8 is ditto, viewed at right angles, and Fig. 9 a plan of an arrangement of parts slightly differing in construction from that of the foregoing figures. Fig. 10 is a section of the series of 35 lifters and of a pair of handles instead of the knob for operating them. Fig. 11 shows in a vertical section a single handle for the same purpose. Fig. 12 is a perspective 40 view showing the valve stem, guide, pin, and lifter with the addition of an incline above the pin, by which the valve may be forced down, &c.

Description with reference to the drawings.— 45 The body of the faucet is marked *a* and the valve *b*. The water enters at *c*, and when the valve is lifted from its seat, escapes through *d*.

e is a rubber spring, which closes the valve

when it is not forced open and also prevents 55 leakage at the joint of the cap and around the valve-stem, as shown in a previous patent granted to me.

f is the cap or gland. Upon this cap is cast or otherwise secured the guide *g*. In 60 this guide are slots which allow the pin *h* to play up and down freely with the valve-stem *i*, in which it is so placed that its ends may project beyond the outer surface of 65 guide *g*.

j is an annular piece fitted loosely around *g* and has one, or a series of two or more inclined surfaces or lifters formed on its upper edge. The highest point of these inclines is of such an elevation that when the 70 pin *h* rests thereon the valve will be raised from its seat sufficiently to give the full requisite flow of water, and the lowest part so low that the pin *h* will not quite rest upon it when the valve rests upon its seat. An 75 inverted cup-shaped piece *k* is fitted to *j* and secured by two screws or pins *l*. Its upper part is formed into a knob, as in Figs. 1, 3, 6, or has attached a handle, as in Fig. 11, and has also a pivot *m*. 80 *n*, is a step which supports pivot *m*, and rests on guide *g*.

When the faucet is to be put together, the valve *b*, and spring *e*, are first put in their place, then the gland or cap *f* is screwed 85 down to its place, a hole is then made through the valve-stem corresponding to the position of the slots in the guide *g*, (or if the hole in the valve-stem is already made, it should be so placed that when the cap is 90 screwed down it will coincide with the slots in the guide), then the pin is slipped through the slots and the hole in the valve-stem, and step *n*, placed upon *g*, after which *k*, is 95 dropped on over the whole and secured to *j*, as described. The pin *h*, can not then get out of place even if it were loose in the valve-stem.

The operation is as follows: The hand being applied to the knob or handle, turns *k*, either way when the lifters on *j* begin to act on the pin *h*, and the guide *g* preventing it with the valve-stem from being turned around the valve is thereby lifted from its seat until the pin has reached the highest 105 point of the inclines, when if turned either way it will close again, or if left on either incline it will close of itself by the force of

the spring. A slight notch may be formed on the elevation between two inclines on *j*, so that the valve may remain open without the trouble of holding on, if desired. The 5 pivot *m* may be dispensed with, as when the handles are applied directly to the lifters, see Fig. 10, in which case *j* rests directly upon the cap *f*, but will not work quite so free as when supported by pivot *m*.

10 Figs. 7, 8, and 9 show a modification, by means of which no care is required in screwing down the gland *f*, to have the hole in the valve-stem coincide with the slots in the guide to allow the pin to play up and down 15 freely in them. But the valve-stem has a groove around its upper end and the pin is made in two parts, which are held in piece *o*, their inner ends playing in the groove in the valve stem and the outer ends being 20 acted on by the lifters as before described. In this case the guide is adapted to the piece *o* instead of the pin.

In Fig. 12, *p* is the part corresponding to *j* in the other figures and has an inclined 25 part above as well as below the pin *h*. The part above forces the valve down in like manner, as the part below lifts it up. The pins *q* are to hold *p* down, and prevent its

rising when turned, so as to force the valve down.

With these improvements the knob may be turned either way or be lifted up, and in either case the valve will be opened with equal certainty, except when arranged as in Fig. 12, for locking down the valve, in which case by turning one way the valve is lifted up, but by turning the other way it is closed and locked down.

The number of inclines, as well as the degree of inclination can, of course, be varied 40 according to circumstances.

Having thus described my improvements, what I claim as my invention and desire to secure by Letters Patent, is as follows:

1. The combination of the annular lifter 45 or lifters, guide, and pin, substantially as described, with or without the top incline for closing the valve shown in Fig. 12.

2. I also claim pivoting the annular lifter or lifters at *m*.

March 3d, 1857.
